UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

REFLECTOR-SOCKET.

981,240.

Specification of Letters Patent. Patented Jan. 10, 1911.

Application filed November 3, 1906. Serial No. 341,918.

To all whom it may concern:

Be it known that I, REUBEN B. BENJAMIN, a citizen of the United States, residing at Chicago, in the county of Cook and State of Illinois, have invented new and useful Improvements in Reflector-Sockets, of which the following is a full, clear, concise, and exact description, reference being had to the accompanying drawing, forming a part 10 of this specification.

My invention relates to improvements in lamp sockets, one of the objects of my invention being to provide a lamp socket with the axis thereof in a plane substantially parallel with the plane of the wall or other supporting part to which the lamp may be fixed.

Another object of my invention is to provide means in a socket of this character, whereby access may be readily had to the 20 binding posts thereof.

I have illustrated in the accompanying drawings one form of socket for the purpose of disclosing my invention, and in said drawings, Figure 1 is a side elevation of my 25 socket with a part of the same broken away to show the construction; Fig. 2 is a sectional view taken on the line 2—2 of Fig. 1; Fig. 3 is a bottom plan view; Fig. 4 is a section on the line 4—4 of Fig. 2; and Fig. 5 is 30 a partial view of a modified form of base.

In the construction of my invention I provide a base 1, of minimum transverse section and preferably formed of porcelain. This base is recessed or cut away as at 2 at its top, 35 and the central portion of a metallic strip 3 rests therein, having its ends 4 bent downwardly. The extremities of the ends 4 project slightly beyond the center of the base, and are arranged away from the sides there- 40 of so they may spring. A screw 5 having its head bearing upon the upper side of said plate 3 extends downwardly through the base and screws the plate in position. A threaded lamp receiving shell 6 is arranged 45 on either side of the base 1, and is secured thereto by means of a screw 7 which passes through the base and connects the two shells. The head of the screw bears upon an in-turned portion 8 of one of the shells and screws into a corresponding in-turned portion 50 on the opposite shell. The side of the base opposite the screw 7 is recessed or cut away as at 9, and the central portion of a metallic strip 10 rests therein, being held in position

by a screw 11, the head of which bears upon 55 the top of said strip, and the threaded end of which extends to the base. The ends 12 of the strip 10 are bent upwardly and are secured to the inturned portions 13 of the shells 6 by screws 14, which pass through 60 said inturned portions and screw into the ends 12 of the strips.

A preferably cylindrical casing 15 surrounds the shells and an insulating sheath 16 is interposed between the casing and the 65 shells. The casing 15 is preferably formed of two pieces which telescope upon one another, and form an inclosing casing for the 70 lamp socket.

The base 1 of the socket has an off-set 17 which extends at right angles to the axis of the shells 6 and has formed in its lower end channels 18 through which may pass the supply wires of the socket. Extending substantially at right angles to the channels 18 75 and longitudinal of the off-set 17 are additional channels 19 in which are arranged a pair of contact plates 20, having angular extensions 21^a with which the ends of the screws 11 and 5 are arranged to engage, 80 whereby the screws are mechanically held in position and electrical connection is established between the contact plates 20 and the contact members of the lamp. The contact plates 20 carry a pair of binding posts 85 21, by which the supply wires of the socket are attached to the plates. The channels 19 at points on the sides of the off-set 17 are opened whereby access may be obtained through the sides of the off-set to the binding posts arranged therein. A preferably cylindrical casing 22 surrounds the off-set 17 and screws upon screw threads 23 formed on the extension over the openings in the 90 sides of the off-set whereby the binding posts are suitably inclosed. By raising the casing 22 ready access may be had to the binding posts. At the bottom of the off-set 17 is formed a flange 23 having openings 24 formed therein, through which screws may 95 pass for securing the socket in position. In the modification illustrated in Fig. 5, I have shown a different form of base having a projection 25 formed thereon, below the flange 23 which may fit into an opening in a 100 suitable casing in which the supply wires are arranged.

Having thus described my invention what

I claim as new and desire to secure by Letters Patent is:

1. A lamp socket comprising a lamp receiver and center contact, an insulating base having a supporting off-set substantially at right angles to the axis of the receiver, said off-set having recesses, binding posts mounted in said recesses, means for obtaining access to said binding posts from the sides of the off-set, and a movable cover normally closing said last-named means.
2. A lamp socket comprising a lamp receiver and center contact, an insulating base associated therewith and having a supporting off-set substantially at right angles to the axis of the lamp receiver, said off-set having transverse channels in the bottom thereof, through which the supply wires are arranged to pass, and recesses communicating with said channels, binding posts arranged in said recesses, and means for obtaining access to said binding posts from the sides of the off-set.
3. A lamp socket comprising a lamp receiver and center contact, an insulating base associated therewith having a supporting off-set substantially at right angles to the axis of the lamp receiver, said off-set having a flange for securing the same upon a suitable support and having recesses formed therein, binding posts arranged in said recesses, means for obtaining access to said binding posts from the sides of said off-set, and a member normally concealing said

binding posts and made movable to expose 35 the same.

4. A lamp socket comprising a lamp receiver and center contact, an insulating base associated therewith having a supporting off-set substantially at right angles to the axis of the lamp receiver, a flange formed on said off-set for securing the same to a suitable support, said off-set having channels in the bottom thereof through which the supply wires are arranged to pass, and recesses communicating with said channels, binding posts arranged in said recesses, and means for obtaining access to said binding posts at the front of the flange.

5. A lamp socket comprising an insulating base, a pair of lamp receivers and associated contacts arranged on opposite sides of said base, a supporting off-set formed on said base at substantially right angles to the axis of said lamp receivers, said off-set having recesses formed therein, binding posts mounted in said recesses, means for obtaining access to said binding posts from the sides of the off-set, and a rotarily mounted cover-piece normally closing said last named 60 means.

In witness whereof, I have hereunto subscribed my name in the presence of two witnesses.

REUBEN B. BENJAMIN.
